UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 29, 1926. Serial No. 125,764.

My invention relates to railway traffic controlling apparatus, and particularly to apparatus of the type wherein train carried governing mechanism is controlled by energy received from the trackway. More particularly my present invention relates to the trackway portion of such apparatus.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway along which traffic normally moves in the direction indicated by the arrow. These rails are divided by insulated joints 2 into a plurality of track sections, of which only one complete section A—B is shown in the drawing. Located at an intermediate point in this section is a drawbridge C, which controls a contact 13 in such manner that the contact is closed when the drawbridge is closed and locked, but is open when the drawbridge is open or unlocked.

Alternating track circuit current is supplied to the rails of section A—B by a transformer T^B, the secondary of which is constantly connected across the rails adjacent the point B, and the primary of which is constantly supplied with alternating current from a source which is not shown in the drawing.

Means are also provided for supplying the section with train governing current which flows through the rails of the section in multiple, and which I will hereinafter term "loop" current. For this purpose an impedance 3 is connected across the rails of the section adjacent the point A, a second impedance 4 is connected across the rails immediately in advance of the drawbridge C, and a third impedance 5 is connected across the rails adjacent the point B. Train governing current is supplied by a transformer L^B, the primary of which is constantly connected with the same source of alternating current as that which supplied the primary of transformer T^B. The relative polarity of the train governing current is controlled by track relay R^B for the section next in advance of the point B. When track relay R^B is energized and the draw-

bridge C is closed and locked, train governing current flows from the right-hand terminal of the secondary of transformer L^B, through front contact 6 of track relay R^B to the mid-point of impedance 5 and then through the rails 1 and 1^a in multiple to impedance 4, and from the mid-point of this impedance, through wire 14, contact 13, wire 12, winding of a relay X, wire 8, and front contact 7 of relay R^B to the left-hand terminal of the secondary of transformer L^B. When relay R^B is de-energized, the circuit for the train governing current is the same, but the relative polarity of the current with respect to the track circuit current is reversed because of the pole-changing action of contacts 6 and 7 of relay R^B.

When contact 13 is open, relay X is de-energized, whereupon back contact 10 of this relay connects wire 8 with the mid-point of the second impedance 4. The train governing circuit is then from the right-hand terminal of the secondary of transformer L^B, through front contact 6 of relay R^B to the mid-point of impedance 5, then through the rails 1 and 1^a in multiple to impedance 4, and from the mid-point of this impedance through wire 11, back contact 10 of relay X, wires 9 and 8, and front contact 7 of relay R^B to the left-hand terminal of the secondary of transformer L^B.

The trackway apparatus herein shown and described, is intended for co-operation with train-carried governing mechanism in such manner that a proceed indication is given aboard the train. When the train occupies a portion of track which is supplied with train governing current of normal relative polarity and with track circuit current, a caution indication is given aboard the train when the track is supplied with train governing current of reverse relative polarity and with track circuit current, whereas a stop indication is given aboard the train when the supply of either train governing current or track circuit current or both is discontinued.

It will be seen from the foregoing that when the drawbridge C is closed and locked, both track circuit current and train governing current are supplied to the section A—B throughout the entire length of this section, whereas when the drawbridge C is unlocked, the supply of both track circuit current and

train governing current is discontinued from the entrance end A to the drawbridge C; track circuit current however, is supplied to the rails from the drawbridge to the exit end B, and since relay X is de-energized train governing current is also supplied to this portion of the section. It follows that if drawbridge C is unlocked while a train is between this drawbridge and the exit end B, such train will receive a proceed or a caution indication according to the condition of relay R⁸, although, of course, a train located between point A and the drawbridge C will receive a stop indication. In other words, the drawbridge C may be unlocked and opened after a train has passed this drawbridge and is still in the section A—B without stopping the train.

Although I have herein shown and described only one form of apparatus embodying my invention, it is understood that various changes and modifications may be made therein within the scope of the appended claims without departing from the spirit and scope of my invention.

Having thus described my invention what I claim is:

1. In combination, a section of railway

track, a drawbridge located at an intermediate point in said section, a main train governing circuit for said section including the rails of the section from end to end as well as the winding of a relay and a contact operated by said drawbridge, and an auxiliary train governing circuit for said section including the rails from said intermediate point to the exit end of said section and a back contact of said relay.

2. In combination, a section of railway track, a drawbridge located at an intermediate point in said section, three impedances connected across the rails of said section at the entrance end and immediately in advance of said drawbridge and at the exit end respectively, a source of train governing current having one terminal connected with said third impedance and its second terminal connected with said first impedance through the winding of a relay and a normally closed contact which is opened when the drawbridge is open, and means including a back contact of said relay for connecting the second terminal of said source with said third impedance.

In testimony whereof I affix my signature.
RONALD A. McCANN.
